J. ERICKSON.
MEASURED SERVICE TELEPHONE SYSTEM.
APPLICATION FILED SEPT. 18, 1918.

1,358,945.

Patented Nov. 16, 1920.

—Inventor—
John Erickson
John V. Vales, Atty.

UNITED STATES PATENT OFFICE.

JOHN ERICKSON, OF CHICAGO, ILLINOIS, ASSIGNOR TO AUTOMATIC ELECTRIC COMPANY, OF CHICAGO, ILLINOIS, A CORPORATION OF ILLINOIS.

MEASURED-SERVICE TELEPHONE SYSTEM.

1,358,945.

Specification of Letters Patent. Patented Nov. 16, 1920.

Application filed September 18, 1918. Serial No. 254,565.

To all whom it may concern:

Be it known that I, JOHN ERICKSON, a citizen of the United States of America, and a resident of Chicago, in the county of Cook 5 and State of Illinois, have invented certain new and useful Improvements in Measured-Service Telephone Systems, of which the following is a specification.

My invention relates in general to a 10 measured service automatic telephone system, and more specifically to a pay station device for use in an automatic telephone system.

Among the objects of my improved pay 15 station are to provide a prepayment coin collector which requires the deposit of a coin before a call can be completed, and one which includes means for releasing the extended connection when the called subscriber answers in case the coin has not been 20 deposited.

These and other objects and features of 25 my invention will be more clearly pointed out and explained in the following specification:

In the drawing I have shown only that part of an extended connection which is essential to the operation of the coin device. The substation A having a line switch of 30 any type for selecting an idle connector switch which is in turn operated to pick out the line of a called subscriber. I have shown only the line wipers of the line switch and the line and reversing or back bridge relays 35 of the connector. It will be understood also that selectors may be inserted between the line switch and the connector and also that said line switch and connector may be of any type in which the back bridge relay 40 operates to reverse battery upon the response of the called subscriber.

At M, I have shown the essential parts of the coin collector in diagrammatic form associated with the line of the substation A.

45 When the subscriber at A removes his receiver to initiate a call a circuit is closed from battery at the coils of the line switch over line conductor 2, springs 3, polarized relay 4, transmitter 5, receiver 6, calling device springs C. D. springs 7 and 8 and conductor 9 back to ground and battery through the line switch. Although relay 4 is included in this circuit it does not operate, as the current now tends to draw the lower

end of the armature 10 toward the lower 55 pole piece of the magnet but is not strong enough to overcome the tension of springs 3.

The subscriber before continuing the call must now deposit a coin in the slot of the coin box. As the coin is deposited it falls 60 upon the upper end of a plunger 11 which is mounted in the armature 10 of the polarized relay 4. This plunger has a spiral spring inside the armature 10 which normally tends to hold the same in its uppermost position, 65 but which is weak enough so that the weight of the coin on the upper end is strong enough to compress the spring and force the plunger to its lowest position as shown in the drawing.

70 The plunger when thus pressed down, operates to close the springs 12 at the lower end thereof, and removes the catch 13 from engagement with the arm 14. The subscriber may then proceed to dial the wanted 75 number by means of the calling device C. D. during which operation, the polarized relay 4 and the transmitter and receiver are short circuited by means of the shunt springs 15 to prevent annoyance to the subscriber or 80 false operation of the polarized relay. When the receiver was first removed the line switch C, only the wipers of which are shown, operated to automatically extend the connection to an idle one of a plurality of connector switches H. The operation of the calling device now controls the line relay 16 of the connector H to bring the wipers of said switch into connection with the desired subscriber's line in the usual manner, 85 whereupon the said connector operates to project signaling current over the called subscriber's line to signal the subscriber. As soon as the subscriber at B lifts his receiver 90 in response to this signal, a circuit is closed 95 for the back bridge relay 17 in series with the called line and battery. Relay 17 energizes and reverses the connections of the windings of the line relay 16 with regard to the line conductors leading to the calling 100 station, thereby reversing the flow of current in the calling subscriber's line circuit and through the polarized relay 4. This reversal of current through relay 4 causes relay 4 to attract the upper end of armature 10 to the upper pole piece of said relay, 105 thereby removing the upper end of the plunger to the right and allowing the coin to

pass down the left hand chute and be collected. A further result of the attraction of this armature is the closing of the springs 18 by means of the part 19, and the result-
5 ant short circuiting of the polarized relay 4.

Conversation may now proceed over the heavy conductors shown, and after conversation is completed the switches are restored and the connection released in the usual
10 manner by the restoration of the receiver of the calling subscriber to the switchhook. As the hook is restored, the springs 8 and 20 are brought into contact, thereby closing a circuit which was prepared by the springs
15 12 when the coin was inserted. The closure of this circuit in series with the line circuit and battery passes through said springs 8 and 20 magnet 21, springs 12, and conductor 2 to the other side of battery at the line
20 switch. The magnet 21 being of high resistance alone energizes over this circuit and operates to attract its armature 22 to rotate the arm 23 about its axis and also to close the springs 3 in case they had been operated.
25 The rotation of arm 23 operates, through the medium of the link 25 to again draw the armature 10 and its plunger, back to normal position, thereby causing arm 19 to pass out from under the springs 18, opening the same, and also when arm 19 disengages springs 18, the plunger 11 moves back to its uppermost position and opens the springs 12 in the circuit of the release magnet 21.

30 35 Now assume that the subscriber at A attempts to set up a call without first depositing a coin in the slot. In this case the operation will proceed as usual except that arm 13 will not be removed from under arm
40 14 due to the fact that the plunger 11 of the coin collector has not been forced downward by a coin. Therefore when the called subscriber answers the call and battery is reversed by relay 17 of the connector, the
45 relay 4 will attract its armature as before toward the upper pole piece, but will in this case also draw the arm 14 up by means of part 13 and thereby cause springs 3, which have been held together, to open their contact. The opening of springs 3 opens the line circuit to the automatic switches and causes the release of the connection in the same manner as when the receiver is restored. Also when armature 10 is attracted
50 55 the lower end thereof rides up on the projection 26 and closes contact of springs 12 in the circuit of the release magnet. Now the subscriber must hang up his receiver, operate magnet 21 to again restore armature
60 65 10 and call again.

It will be seen therefore that I have designed a very simple coin collecting device of the prepayment type which makes it necessary for the coin to be deposited before calling or at least before the response of the

called subscriber, and one which releases an entire connection when the called man answers, in case the coin is not first deposited.

Having fully described and ascertained the features and aspects of my invention, 70 what I consider to be new and desire to have protected by Letters Patent will be pointed out in the appended claims.

What I claim as my invention is:

1. In a telephone system, a pair of lines, 75 means for establishing a connection between said lines, a coin collector for the calling line, means controlled by the response of the called subscriber for collecting a coin when deposited in said collector and for releasing 80 the entire connection if the coin is not deposited.

2. In a telephone system, a pair of lines, a plurality of automatic switches for establishing a connection between said lines, a 85 coin collecting device for the calling line, means controlled by the response of the called subscriber for collecting a coin when deposited before the call, and for releasing all of said switches if the coin is not de- 90 posited.

3. In a telephone system, a pair of lines, means for establishing a talking circuit between said lines, a coin collecting device for the calling line, means controlled by the 95 subscriber on the called line for collecting a previously deposited coin in said device, and for opening said talking circuit to release the connection between said lines if a coin is not previously deposited. 100

4. In a telephone system, a pair of lines, means for establishing a talking circuit between said lines, a coin collecting device for the calling line, means controlled by the subscriber on the called line for collecting a previously deposited coin in said device, 105 and for opening said talking circuit to release the connection between said lines if a coin is not previously deposited, and means controlled by the restoration of the receiver at the calling substation for again closing said talking circuit.

5. In a telephone system, a pair of lines, means for establishing a talking circuit between said lines, a coin collecting device for the calling line, means controlled by the subscriber on the called line for collecting a previously deposited coin in said device, 115 and for opening said talking circuit to release the established connection if a coin is not previously deposited, and means controlled by the restoration of the receiver at the calling substation for again closing said talking circuit. 120

6. In a telephone system, a pair of lines, 125 means for establishing a connection between said lines, a coin collecting device for the calling line, a relay in said device, means controlled by the response of the called subscriber for operating said relay to collect a 13

previously deposited coin, and for operating said relay to release said connection when a coin is not deposited.

7. In a telephone system, a magnet, an armature for said magnet, a movable plunger in said armature, a pair of springs operated by said plunger independent of said magnet, another pair of springs always operated by said plunger when the magnet is energized, and another pair of springs operated by said plunger when the magnet is energized only in a certain position of said plunger.

8. In a coin collecting device, a magnet for controlling the collection of a coin, an armature for the magnet, a movable plunger mounted in said armature and adapted to be controlled by the depositing of a coin, a circuit controlling said plunger when a coin is deposited, another circuit controlled by said plunger when the magnet is energized, and another circuit controlled by said plunger only when a coin is deposited and the magnet is energized.

25 9. In a telephone system, a coin collecting

device, a magnet for controlling the collection of a coin, an armature for said magnet, a plurality of contacts controlled by said armature, said armature normally operative to operate all of said contacts when the magnet is energized, and inoperative to operate certain of said contacts if a coin is deposited in the device.

10. In a telephone system, a pair of lines, means for establishing a talking circuit between said lines, a coin collecting device for the calling line, a magnet for controlling the operation of said device, means controlled by the removal of the receiver at the called substation to energize said magnet to collect the coin, and means controlled by the energization of said magnet for opening the talking circuit to release the connection if the coin is not deposited and a second magnet controlled by the calling subscriber for again closing said talking circuit.

Signed by me at Chicago, Cook county, Illinois, this 11th day of September, 1918.

JOHN ERICKSON.
